UNITED STATES PATENT OFFICE

105,254

DESIGN FOR A FAUCET HANDLE OR SIMILAR ARTICLE

Roy H. Zinkil, Oak Park, Ill., assigner to Crane
Co., Chicago, Ill., a corporation of Illinois

Application March 5, 1937, Serial No. 68,013

Term of patent 14 years

To all whom it may concern:

Be it known that I, Roy H. Zinkil, a citizen of the United States, residing at Oak Park, in the county of Cook and State of Illinois, whose post office address is 406 North Cuyler Avenue, Oak Park, Illinois, have invented a new, original,
and ornamental Design for Faucet Handle or Similar Article, of which the following is a specification, reference being had to the accompanying drawing, forming part thereof.

Fig. 1 is a perspective view of the handle showing my design.

Fig. 2 is a plan view.

Fig. 3 is an end view.

Fig. 4 is a side view.

I claim:

The ornamental design for a faucet handle or similar article, substantially as shown.

ROY H. ZINKIL.
